UNITED STATES PATENT OFFICE.

WILLIAM E. STEVENS, OF NEW HAVEN, CONNECTICUT, ASSIGNOR TO SARGENT AND COMPANY, OF NEW HAVEN, CONNECTICUT, A CORPORATION OF CONNECTICUT.

DESIGN FOR COFFIN-TRIMMING.

SPECIFICATION forming part of Design No. 36,219, dated February 3, 1903.

Application filed December 26, 1902. Serial No. 136,754. Term of patent 14 years.

To all whom it may concern:

Be it known that I, WILLIAM E. STEVENS, of the city and county of New Haven, State of Connecticut, have invented a new, original, and ornamental Design for a Casket-Trimming, of which the following is a full, clear, and exact description, when taken in connection with the accompanying drawings, which form a part thereof, and in which—
5 Figure 1 represents a front view, and Fig. 2 an edge view, of a casket-trimming embodying my design.

In both figures similar letters of reference represent like parts.

15 My invention relates to a design for a casket-trimming; and the design consists of the configuration and ornamentation, as herein-after described, and shown in the accompanying drawings.

20 The design is herein shown applied to a socket-plate for a handle; but it will be observed that it is equally applicable to plain casket-plates.

25 The trimming consists of a straight molding A, which extends entirely across the plate and divides it horizontally. Above the molding A is a recess B, in which is a series of convex protuberances C, surrounded by an

intertwining band D, which crosses itself between adjoining protuberances. Above the recess B is a medallion E, bounded by scrolls F, terminating on its sides. Emanating from the direction of the medallion and on both sides of it is a series of scroll-like figures G, curving outward and downward. The portion H beneath the molding A is rounded out, as more particularly shown in Fig. 2, and has in its center a medallion I, bounded by scrolls K, terminating above and below it. Emanating from the ends of the molding A, following the contour of the lower portion H and branching on both sides of the medallion I, are two sprays L of conventionalized foliage.

30 Having now described my invention, what I claim, and desire to secure by Letters Patent, is—

35 The ornamental design for a casket-trimming, as herein shown and described.

40 In witness whereof I have hereunto set my hand on the 16th day of December, 1902.

W. E. STEVENS.
